UNITED STATES PATENT OFFICE.

WILLIAM PINET, OF VONDA, SASKATCHEWAN, CANADA.

GRAIN-CAR DOOR.

1,393,962.

Specification of Letters Patent.

Patented Oct. 18, 1921.

Application filed December 9, 1920. Serial No. 429,470.

To all whom it may concern:

Be it known that I, WILLIAM PINET, subject of the King of Great Britain, residing at Vonda, in the Province of Saskatchewan, Canada, have invented certain new and useful Improvements in Grain-Car Doors; and I do hereby declare that the following is a full, clear, and exact description of the invention, such as will enable others skilled in the art to which it appertains to make and use the same.

The present invention relates to new and useful improvements in grain car doors.

The primary object of the invention is the provision of a grain car door, provided with a suitable supporting frame, by means of which the latter can be moved longitudinally of the car, to and from the door opening, and transversely of the car into said opening and in closed position.

Another object of the invention is the provision of a supporting means for the door by means of which the same can be swung inwardly into the doorway of the car, for the purpose of sealing the same against the leakage of the grain therefrom.

Still another object of the invention is the provision of a grain car door including a supplemental door through which grain can be fed into the car without opening the main door.

A further object of the invention is the provision of a supporting means for the door by which the same can be moved inwardly, flush with the inner side of the car and held against any undesired movement.

A still further object of the invention, is the provision of a grain car door such as above referred to, which will be comparatively simple and inexpensive to manufacture, reliable and efficient in use, and readily operated.

With the above and other objects in view, the present invention resides in the novel features of construction, formation, combination, and arrangement of parts, to be hereinafter, more fully described, claimed and illustrated in the accompanying drawings, forming a part of the present application, and in which:

Figure 1 is a perspective view, of a portion of one side of a grain car showing a door therein, in closed position;

Fig. 2 is a horizontal sectional view, thereof;

Fig. 3 is a similar view, showing the door moved outwardly ready for sliding movement.

Fig. 4, is a vertical sectional view, taken through the door showing the same in closed position; and,

Fig. 5 is a similar view, showing the door in its outer position ready for sliding movement.

Referring now to the accompanying drawings by corresponding characters of reference, throughout the several views, the numeral 5 designates a grain car, comprising a side member 6 and a top 7, and bottom 8.

The outer side 6 of the car is provided with a suitable door opening 9 which is adapted to be closed by the door 10.

The door 10 comprises a sliding body 11 and an outer supporting frame 12, which is mounted within suitable guides 13 secured to the outer side 6 of the car 5.

The door frame 12 is supported on the track 14 and is limited in its sliding movement on the track, in the direction of the door frame 9 by the stops 15.

The frame 12 comprises opposite side members 16, a top member 17 and bottom member 18. From the side members 16 extend forwardly directed brackets 19 in which are journaled the upper and lower crank members 20 and 21, the arched portion 22 of which pass through the sliding blocks 23 and 24, which are mounted on guides 25, secured to the forward side of the door 11. Upon vertical movement of the blocks 23 and 24 on guides 25 the crank members 20 and 21 are swung radially from their pivotal connection in brackets 19 as illustrated by the arrows in Fig. 4, thus moving the door horizontally either interiorly or exteriorly as required.

The blocks 23 and 24 upon opposite sides of the door are connected by a rod 26 which holds them in their proper spaced positions relative to each other.

The intermediate portions of the arches 22 of the crank members 20 are connected by a bar 27, which is connected at its opposite ends to the intermediate portions of the said arches 22. This bar passes through a guide member 28 in which it is slidably mounted and is provided with a suitable handle 29 by means of which the said bar 27 can be raised and lowered and the cranks 20 and 21

21 swung outwardly or inwardly and the door 11 forced from the position in Fig. 5 of the drawing, to the position shown in Fig. 4 in which it can be locked by the latch members 5 30. These latch members are formed from flat metal bars and are pivoted adjacent their ends in slots formed in the door frame. When the door is open the latch members 10 are normally in a vertical position in the slots and are out of the path of the door but when the door is in the position as shown in Figs. 1 and 2, the latch members are dropped to a horizontal position and engage the outer side of the door to reinforce the 15 locking means.

The bar 27 may likewise be provided with a plurality of perforations 31 through which a locking pin 32 passes. The pin 32 is carried by the guide member 28, and obviously 20 when in locking position will hold the door, either in its inward or outward position, against any undesired movement.

The door 11 is likewise provided at its upper end with a supplemental door 33 25 which is hinged at its upper end and can be forced inwardly as shown in dotted lines in Fig. 4 in which position it is held by the latch 34. When in the dotted line position shown in Fig. 4, the grain may be fed into 30 the car therethrough.

When in the position shown in Figs. 2 and 4 the door will be held against any undesired movement but when in the position shown in Figs. 3 or 5 the door may be moved 35 longitudinally of the car, out of the path of the doorway and access may be had to the car, as desired.

From the foregoing description taken in connection with the accompanying drawings, it will be manifest that a door for grain 40 cars is provided which will fulfil all of the necessary requirements of such a device, and it should be understood in this connection, that various minor changes in the specific 45 details of construction, can be resorted to within the scope of the appended claims, without departing from the spirit or sacrificing any of the advantages of the invention.

Having thus fully described my invention, 50 what I claim as new and desire to protect by Letters Patent is:—

1. The combination in a grain car, of a door, a sliding frame in which the door is mounted, cranks connected to said frame, 55 blocks slidably mounted upon said door, and connected to said cranks, a connection between said cranks and an arm secured to the said last mentioned connection, whereby the

blocks can be raised and lowered substantially as and for the purposes set forth. 60

2. In the device of the character described, the combination of a grain car, including a doorway, a frame slidably mounted upon said car, a door mounted in said frame, cranks operatively connecting said door to the door frame, said connection comprising blocks slidable upon said door and receiving said cranks, means for connecting the blocks together to prevent their relative movement, means for connecting said cranks, 70 an arm secured to said last mentioned means, a guide for said last mentioned means, and a pin carried by the guide and engaging said last mentioned means, substantially as and for the purposes set forth. 75

3. In a device of the character described, the combination with a grain car, of a frame slidably mounted thereon, to and from the door opening of said car, a door mounted in said frame, cranks operatively connected to the sides of the frame, blocks through which said cranks pass, means for slidably mounting said blocks upon said door, means for connecting the blocks in pairs to prevent their relative movement, a bar connecting 85 said cranks, an operating arm secured to said bar, a guide secured to the door through which said bar passes, a pin carried by the guide to enter openings formed in the bar, for locking the door in open and closed position, and means for additionally locking the door in closed position. 90

4. In a device of the character described the combination in a grain car, having a door opening in its side, a track upon the side of 95 said car, a frame mounted upon the track, a door mounted in said frame, cranks connected to the opposite sides of the door at the upper and lower ends thereof, blocks 100 slidably mounted upon said door for connecting the cranks to the door, brackets provided upon the door for receiving the ends of said cranks, bars connecting the blocks in pairs upon opposite sides of the door, a bar connecting the intermediate portions of the cranks, a guide through which said bar passes, said bar having openings 105 therein, a pin passing through the guide for engagement with the openings in the bar, an operating arm secured to said bar, 110 and a supplemental door provided in the first named door of the car, substantially as and for the purposes set forth.

In witness whereof I have hereunto set my hand.

WILLIAM PINET.
